CLAIM

The ornamental design for a gas gun for shrink-wrapping, showing my new design.

DESCRIPTION

FIG. 1 is a right side elevational view of a gas gun for shrink wrapping showing my new design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a perspective view of the top, front and right side thereof; and,

FIG. 8 is a perspective view of the top, rear and left side thereof.

The elements shown in broken lines are not part of the present design.
